BABY BOTTLE AERATOR

William E. Lauterbach, Chicago, Ill.

Application November 2, 1949, Serial No. 125,117

5 Claims. (Cl. 215—11)

1

The present invention relates to a bottle aerator and more particularly to an aerator for venting the interior of a nipple-type bottle to circumambient pressure without interrupting the dispensing of liquid therefrom.

As is well known, during the dispensing of liquid from a nipple-type bottle, such as a baby bottle, the decrease in liquid level within the bottle creates a partial vacuum therein, causing the collapse of the nipple, thus seriously hindering the further dispensing of liquid from the bottle.

Various means and procedures have been proposed for venting the interior of the bottle to the atmosphere, including the time honored procedure of removing the bottle from the baby's mouth and holding the bottle upright to permit the entrance of air. This of course interrupts the feeding procedure, and in order to remedy this fault numerous forms of special bottles and nipples have been proposed. However, such special bottles and nipples have not met with wide acceptance for one reason or another, including the expense of the apparatus, the inconvenience involved in its use, the tendency for leakage of the liquid through the openings usually provided for venting purposes, etc.

The present invention now provides an easily employed, simple and inexpensive aerator which may be employed with conventional bottles and nipples, and which permits the venting of the interior of the bottle to circumambient or atmospheric pressure at controlled intervals during the feeding process without the necessity of interrupting the dispensing of liquid therefrom.

More particularly, the present invention provides an improved aerating apparatus including a lever arm having a terminal portion which engages a portion of the nipple overlying the dispensing outlet of the bottle. The arm is pivoted for movement relative to the bottle, and upon movement thereof, the nipple is locally deformed from contact with the bottle to permit venting of the interior of the bottle to atmosphere.

It is, therefore, an important object of the present invention to provide an improved, inexpensive, readily employed aerator for a baby bottle.

Another important object of the present invention is to provide an improved baby bottle aerator including means for locally deforming the bottle nipple from sealing engagement with the bottle to vent the interior thereof to atmospheric pressure through the dispensing orifice of the bottle.

2

It is a further important object of the present invention to provide an improved aerator for a bottle provided with a dispensing nipple, the aerator being adapted for use with bottles and nipples of conventional, commercially available design, and the venting of the interior of the bottle to atmosphere being accomplished without interfering with the dispensing of liquid from the bottle.

10 Still another important object of the present invention is to provide an improved baby bottle aerator including an elongated lever arm pivoted intermediate its length to the bottle and having a terminal portion for engaging the bottle nipple, with pivoting movement of the arm relative to the bottle locally deforming the nipple from engagement with the bottle to vent the interior thereof to atmospheric pressure.

Other and further important objects of this 20 invention will be apparent from the disclosures in the specification and the accompanying drawings.

On the drawings:

Figure 1 is a side elevational view, with parts 25 broken away and in section, of a baby bottle provided with an aerator of the present invention;

Figure 2 is a plan elevational view of the bottle of Figure 1;

30 Figure 3 is a front elevational view of the bottle of Figure 1;

Figure 4 is a fragmentary, side elevational view similar to Figure 1 illustrating the operation of the aerator to vent the interior of the bottle to atmospheric pressure;

35 Figure 5 is a fragmentary side elevational view similar to Figure 1 illustrating a modified form of the aerator of the present invention;

Figure 6 is a fragmentary plan elevational 40 view of the embodiment of Figure 5;

Figure 7 is a fragmentary side elevational view of a baby bottle provided with an additional modified form of the aerator of the present invention;

45 Figure 8 is a sectional view taken along the plane VIII—VIII of Figure 7;

Figure 9 is a fragmentary side elevational view similar to Figure 7 illustrating a baby bottle provided with a further modified form of an aerator;

Figure 10 is a sectional view taken along the plane X—X of Figure 9;

Figure 11 is a fragmentary side elevational view, with parts broken away and in section, of 55 a baby bottle provided with still another modi-

filed form of aerator of the present invention; and

Figure 12 is a plan elevational view of the bottle in Figure 11.

As shown on the drawings:

In Figure 1, reference numeral 10 refers generally to a conventional baby bottle comprising a body portion 11 of generally hexagonal cross-sectional configuration (Figure 3) and an elongated tapering neck portion 12 terminating in a radially outwardly extending peripheral annular rim 13. It will be understood that the body portion 11 provides an interior cavity adapted to receive a body of liquid, such as milk, and that the neck 12 and the rim 13 provide a dispensing orifice through which liquid may be dispensed from the interior of the body portion 11.

An apertured nipple 14 of conventional design is secured to the bottle 10 by means of a terminal, annular, peripheral collar 15 which is interiorly recessed to receive the enlarged rim 13. The nipple 14 is preferably made of rubber or other elastomeric substance capable of sealingly engaging the rim 13 and adjacent portions of the neck 12.

The aerator of the present invention, as illustrated in Figures 1-4, inclusive, includes a bracket 17 having opposed resilient spring arms 18 generally conforming to the cross-sectional shape of the body 11 of the bottle 10 and in close gripping contact therewith as shown in Figure 3. The extremities of each of the arms 18 may be turned back, as at 19, to prevent the presence of sharp terminal edges. Each of the terminal arms 18 is formed integrally with a central, upstanding bight portion 20 including opposed closely spaced upstanding legs 20a and a joining web portion 20b (Figure 3).

An elongated rod-like lever arm 21 is provided with an intermediate flat portion 22 entered between the upstanding legs 20a of the bight 20 and pivotally secured therein by means of a pivot pin or rivet 23 extending through registering apertures formed in the flat portion 22 of the arm 21 and the upstanding opposed walls 20a of the bight 20. It will be seen from Figure 1 that the arm 21 extends along the length of the bottle 10 from the bracket 17 and that that portion 24 of the rod 21 extending from the bracket 17 toward the nipple 14 is deflected downwardly toward the nipple. The extreme end 25 of the portion 24 of the arm 21 is of reduced thickness and arcuate in cross-sectional contour to conform to the neck 12, and the reduced portion 25 is interposed between the annular collar portion 15 of the nipple 14 and the neck 12 immediately adjacent the rim 13. The terminal portion of the arm 21 extends from the bracket 17 generally parallel to the axis of the body portion 11 of the bottle 10.

The operation of the aerator of Figures 1-3, inclusive, is illustrated in Figure 4 in which it will be seen that upon depression of the terminal portion 27 of the arm 21, the arm 21 is pivoted about the pin or rivet 23 to elevate the reduced thickness terminal portion 25 thereof. Elevation of the portion 25 lifts the annular collar portion 15 of the nipple 14 from its sealing engagement with the rim 13 and the interior of the bottle 10 is vented to atmosphere through the dispensing orifice of the bottle.

In the second embodiment of applicant's invention as illustrated in Figure 5 of the drawings, reference numerals identical with those of Figures 1-4, inclusive, indicate identical portions of

the bottle, nipple, and bracket. It will be noted that in this modification of the invention the aerator is employed in conjunction with a nipple 14 having a radially outwardly extending ear 30 formed integrally therewith. Such an ear 30 is ordinarily provided to aid in the removal of the nipple from the bottle following use.

A modified form of lever arm 31 is employed in the embodiment of Figures 5 and 6. The arm includes an elongated lever arm proper 31 which is pivoted about a pivot pin 23 secured in the bracket 17 as hereinbefore described in connection with the embodiments of Figures 1-4. That terminal end of the arm 31 overlying the nipple 14 is deformed sharply downwardly to define a dependent portion 32 provided with a terminal extension 33 roughly parallel to the arm 31 and adapted for engaging one side surface of the ear 30. A second bifurcated arm or gripping member 34 is provided with spaced legs extending downwardly on each side of the depending portion 32 of the arm 31, the member 34 being pivotally secured to the portion 32 by means of a pivot pin 35. The lower terminal portion of each of the arms 34 is provided with an inturned portion 36 adapted for engaging the side surface of the ear 30 oppositely engaged by the portion 33 of the arm 32. The upper bight portion 35 joining the arm of the member 34 roughly parallels the arm 31 and a leaf-spring 37 is confined between the arms to urge the bight portion 34 from the arm 31, thus pivoting the terminal portions 36 and 33 into biting engagement with the ear 30.

It will be appreciated that operation of the embodiment of Figure 5 is essentially the same as the embodiment of Figures 1-4, inasmuch as the rotation or pivoting movement of the arm 31 about the pin 23 will cause the elevation of the ear 30 moving the nipple 14 away from engagement with the neck 12 of the bottle 10.

In the embodiment of the invention shown in Figures 7 and 8 of the drawings, the bracket 17 has been eliminated and a different means for causing pivoted movement of a lever arm is provided. The lever arm 40 of the embodiment of Figure 7 is essentially the same as that of the embodiment of Figures 1-4 with the arm including a downwardly extending portion 41 and a terminal portion 42 extending under the lip 15 of the nipple 14 as hereinbefore described. A pivot plate 43 provides a fulcrum for movement of the arm 40, the plate having a lower arcuate edge 44 (Figure 8) conforming to the arcuate exterior surface of the neck 12 and an aperture 45 in spaced relation to the surface 44 for receiving the rod therethrough. The arcuate bottom edge 44 is also rounded transversely of its length to permit smooth rocking motion of the plate upon the edge.

It will be understood that the operation of the aerator of Figures 7 and 8 is essentially the same as that hereinbefore described in connection with Figures 1-4 with movement of the arm 40 toward the bottle 10 causing pivoting movement of the arm and the pivot plate 43 about the arcuate edge 44 to elevate the nipple collar 15 as shown in Figure 4.

In the embodiment of Figures 9 and 10, the pivot plate 43 has been eliminated. More particularly, the lever arm 50 is provided with an integrally formed bight portion 51 which provides a lower, transversely elongated bearing edge 52 similarly positioned and contoured to the edge 44 hereinbefore described in connection with the embodiment of Figures 7 and 8. Actually, the

rod 50 is doubled back upon itself to form a generally oval, integrally formed pivot frame which serves the same function as the plate 43 of Figure 7.

The forward terminal portion 53 of the arm 50 is extended downwardly toward the nipple 14 as hereinbefore described and the terminal extremity of the arm 50 is flat as at 54 for insertion beneath the lip 15 of the nipple 14.

In the embodiment thus seen in Figure 11, the arm 60 extends axially along the length of the bottle 10 as hereinbefore described in connection with the embodiments of the present invention, and the arm may be pivoted by means of a bracket 17 as in the embodiments of Figures 1-6, a pivot plate as in Figures 7 and 8, or an integrally formed pivot frame as in Figures 9 and 10. In any event, the terminal portion of the arm 60 is deformed outwardly and slightly upwardly as at 61 for insertion through an aperture 62 formed in an ear 63 of the nipple 14. The operation of the aerator of Figure 11 and Figure 12 will be obvious from the operation of the other embodiments of the invention hereinbefore described.

Thus, it will be seen that I have provided an improved, extremely simple, readily employed baby bottle aerator adapted for use with conventional, commercially available bottles and nipples. The venting of the interior of the bottle and/or nipple to the atmosphere is accomplished by deforming the nipple from sealing engagement with the neck of the bottle, thus permitting the entrance of air at substantially atmospheric pressures to prevent the formation of partial vacuum within the bottle and the collapse of the nipple. Thus, it is not necessary to interrupt the feeding operation while venting the bottle, nor is it necessary to provide intricately formed relatively expensive, specialized nipples or bottles.

The elongated lever arm extends parallel to the axis of the bottle, so as to be easily grasped by one holding the bottle. Also, the overall bulk of the bottle is not increased materially, thus making the bottle and aerator assembly an easily employed means for feeding a child without the disadvantages heretofore encountered.

In addition to these advantages, it will be seen that a mechanical advantage is obtained by the employment of an elongated lever arm, as shown in each embodiment of the invention illustrated in the drawings. This mechanical advantage makes possible the venting of the interior of the bottle by the application of a moderate pressure to the lever arm, while at the same time permitting the accurate controlling of the extent of deformation of the nipple.

It will be understood that modifications and variations may be effected without departing from the scope of the novel concepts of the present invention.

I claim as my invention:

1. In combination, a bottle having a neck tapering to a rim defining an orifice, a nipple having a resilient distensible and contractible skirt for engaging said rim to cap said orifice, and an aerator for said bottle comprising an operating arm in engagement with said nipple, a handle joined to said operating arm at an angle to form a bent lever, and bearing means carried intermediate the length of said lever to fulcrum the same pivotally relative to said bottle, said bearing means having a concave bottle-contacting surface lying within the angle between said operating arm and said handle to position said handle in spaced relation to said bottle longitudinally

tudinally thereof, whereby pivotal movement of said handle toward said bottle will distend a portion of said nipple skirt away from said bottle rim to vent said bottle.

5. In combination, a bottle having a neck tapering to a rim defining an orifice, a nipple having a distensible and contractible skirt for engaging said rim to cap said orifice, there being an outwardly extending ear formed integrally with said nipple skirt, and an aerator for said bottle comprising an operating arm releasably secured to said ear, a handle joined to said operating arm to form a lever, and bearing means carried intermediate the length of said lever to fulcrum the same pivotally relative to said bottle, said bearing means having a concave surface offset from said lever and in contact with said bottle to position said handle in spaced relation to said bottle longitudinally thereof, whereby pivotal movement of said handle toward said bottle will distend a portion of said nipple skirt away from said bottle rim to vent said bottle.

3. In combination, a bottle having a neck tapering to a rim defining an orifice, a nipple having a distensible and contractible skirt for engaging said rim to cap said orifice, there being an outwardly extending ear formed integrally with said nipple skirt, and an aerator for said bottle comprising an operating arm and a handle joined to form a lever, clamping means secured to said arm and spring-urged to clamp upon said nipple ear, and bearing means carried intermediate the length of said lever to fulcrum the same pivotally relative to said bottle, said bearing means having a concave bottle-contacting surface offset from said lever to position said handle in spaced relation to said bottle longitudinally thereof, whereby pivotal movement of said handle toward said bottle will distend a portion of said nipple skirt away from said bottle rim to vent said bottle.

4. In combination, a bottle having a neck tapering to a rim defining an orifice, a nipple having a distensible and contractible skirt for engaging said rim to cap said orifice, there being an outwardly extending ear formed integrally with said nipple skirt, and an aerator for said bottle comprising an operating arm and a handle joined to form a lever, said nipple ear being apertured snugly to receive said operating arm, and bearing means carried intermediate the length of said lever to fulcrum the same pivotally relative to said bottle, said bearing means having a concave bottle-contacting surface offset from said lever to position said handle in spaced relation to said bottle longitudinally thereof, whereby pivotal movement of said handle toward said bottle will distend a portion of said nipple skirt away from said bottle rim to vent said bottle.

5. In combination, a bottle having a neck tapering to a rim defining an orifice, a nipple having a distensible and contractible skirt for engaging said rim to cap said orifice, and an aerator for said bottle comprising an operating arm in engagement with said nipple, a handle joined to said operating arm at an angle to form a bent lever conforming generally to the profile of the bottle, and bearing means carried intermediate the length of said lever to fulcrum the same pivotally relative to said bottle, said bearing means having a concave bottle-contacting surface lying within the angle between said operating arm and said handle to position said handle in parallel spaced relation to said bottle

longitudinally thereof, said handle being of such length that pivotal movement of said handle against said bottle will distend a portion of said nipple skirt from said bottle rim to vent said bottle.
